CONE-CLUTCH FACING AND PROCESS OF MAKING THE SAME

1,180,885.

Specification of Letters Patent. Patented Apr. 25, 1916.

Application filed November 26, 1915. Serial No. 63,695.

To all whom it may concern:

Be it known that I, ALBERT G. SNIDER, a citizen of the United States, and a resident of Indianapolis, county of Marion, and State of Indiana, have invented a certain new and useful Cone-Clutch Facing and Process of Making the Same; and I do hereby declare that the following is a full, clear, and exact description thereof, reference being had to the accompanying drawings, in which like letters refer to like parts.

The object of this invention is to improve the smoothness and durability of cone clutch facing and also to render the same to some extent yielding and otherwise satisfactory in operation. Heretofore, cone clutches have usually been faced with leather only, which made the surface of the clutch relatively hard and unyielding and not having the frictional coefficient desired. The high quality and character of cone clutch constructions required in automobiles has rendered the improvement herein set forth important and valuable.

The invention consists in making a cone clutch facing with an outer member or surface of leather and securing thereto a lining or inner member of duck or like fabric, and preferably with the longitudinal fibers of the duck or fabric parallel with the lateral edges of the leather portion of the facing. In order to do this, the duck or fabric should be made or woven into a strip having the same width as the facing and securing it to the facing without cutting it along the lateral edges at any point. This, however, is practically impossible in making cone clutch facings unless the duck lining is treated so as to contract one edge thereof sufficiently and uniformly to make it fit straight and smoothly within the leather facing. This is accomplished by stitching the edge desired to be contracted so that the stitches will hold said edge contracted.

The resultant facing, therefore, has a relatively thick lining of fabric with the fibers thereof arranged to fit flat against the leather portion and the longitudinal fibers being parallel with the edges of the leather portion and not being cut at any point along the edges so that the lining is intact from end to end and has all of its strength, and equal strength at all points. Said lining is preferably treated with a material for rendering it oil, water and heat proof. That

makes said facing relatively permanent in character and is sufficiently yielding to give the facing the desired frictional coefficient.

The full nature of the invention will be understood from the accompanying drawings and the following description and claims.

In the drawings, Figure 1 is a perspective view of the cone clutch facing. Fig. 2 is a section on the line 2—2 of Fig. 1, on a larger scale. Fig. 3 is a plan view of the strip of lining which is stitched or prepared for the cone clutch facing, the same being centrally broken away. Fig. 4 is the same after it has been stitched and prepared for said cone clutch facing.

The process of making said cone clutch facing consists in first forming a leather facing strip 10 as usual heretofore. Then the inner surface is trimmed or scraped so that said leather strip will have uniform thickness throughout.

A straight strip of duck 11 is woven and its edges finished and with its longitudinal fibers extending throughout the entire length thereof and parallel with the edges thereof. This strip of duck or other material is like a band with the width thereof the same as the width of the leather strip 10 and the length thereof the same as the largest internal periphery of the leather strip 10.

The next step in the process consists in feeding said duck or fabric strip 11 through a sewing machine and stitching the same near one edge at 12 from end to end and contracting the strip of fabric along the edge being stitched as it is being fed to the needle of the sewing machine, so as to contract said stitched edge equally throughout its entire length and make the strip curved substantially as shown in Fig. 4. The stitch 12 will hold the stitched edge contracted thereafter.

When thus treated, said strip is placed within the leather strip 10 and glued thereto. Because of the curvature given to the strip 11, it will fit smoothly within the leather strip 10 at all points and the longitudinal fibers of the fabric be parallel with the edges of the leather strip or facing and no longitudinal fibers be cut or raveled at the edges of the facing. If the lining for the conical leather strip 10 were cut curved out of a piece of cloth so as to fit straight of said strip 10, a great many of the longi-

tudinal fibers would be cut at, at least, two points, so that the edges would ravel and soon wear and make the clutch facing unsatisfactory and short lived. Such clutch 5 facings would not be satisfactory in machines like automobiles.

The fabric lining is treated preferably with paraffin or any suitable material for rendering the same relatively free from the 10 injurious influences of oil, water and heat which tend to injure and shorten the life thereof.

The invention claimed is:

- 15 1. A cone clutch facing formed of a leather outer member, and a lining member secured thereto consisting of fabric with all of the longitudinal fibers thereof extending parallel with the edges of the outer leather member.
- 20 2. A cone clutch facing formed of a leather outer member, and a lining member secured thereto consisting of fabric with all of the longitudinal fibers thereof extending uncut for the full length of said lining.
- 25 3. A cone clutch facing formed of a conical leather outer member, and a lining member secured thereto consisting of a strip of fabric contracted along one edge so that it will fit smoothly within said outer leather member.
- 30 4. A cone clutch facing formed of a conical leather outer member, a lining member secured thereto consisting of a strip of fabric contracted along one edge so that it will fit smoothly within said outer leather member, and stitches along said contracted edge of the lining member for holding its fibers in contracted position.
- 35 5. A cone clutch facing formed of a leather outer member, a lining member secured thereto consisting of fabric with all of the longitudinal fibers thereof extending parallel with the edges of the outer leather member, and material applied to said lining member for protecting the same from the injurious influence of oil, water and heat.
- 40 6. The process of making a cone clutch facing, which process consists in making an

endless strip of leather suitably conical transversely, making a straight fabric with 50 the longitudinal fibers thereof extending uncut for the full length thereof, contracting said strip of fabric along one edge thereof to enable it to fit flatly within said conical leather strip, and securing said fabric to 55 said strip as a lining with the edges of the fabric and leather strip substantially coterminous.

7. The process of making a cone clutch facing, which process consists in making an 60 endless strip of leather suitably conical transversely, making a straight strip of fabric with the longitudinal fibers thereof extending uncut for the full length thereof, contracting said strip of fabric along one 65 edge thereof to enable it to fit flatly within said conical leather strip, stitching said fabric strip throughout its length along the contracted edge for holding it in its contracted condition, and securing said fabric to said 70 strip as a lining with the edges of the fabric and leather strip substantially coterminous.

8. The process of making a cone clutch facing, which process consists in making an 75 endless strip of leather suitably conical, trimming the interior surface thereof so that said strip of leather would be of uniform thickness throughout and securing to said leather strip a lining member which consists of fabric with all of the longitudinal fibers 80 thereof extending parallel with the edges of the leather strip.

9. The process of making a cone clutch facing, which process consists in making an 85 endless strip of leather suitably conical transversely, securing to said leather strip a lining member which consists of fabric with all of the longitudinal fibers thereof extending parallel with the edges of the leather strip, and treating said fabric with material 90 to protect the same from the injurious influence of water, oil and heat.

In witness whereof, I have hereunto affixed my signature.

ALBERT G. SNIDER.
